ELEVATOR DOOR OPERATOR

Andrew C. Radeff, Jersey City, N. J., assignor to
Westinghouse Electric Elevator Company, Jersey
City, N. J., a corporation of Illinois

Application January 10, 1940, Serial No. 313,241

5 Claims. (Cl. 187—60)

My invention relates to elevator door operators and, more particularly, to operators for elevator doors having an upper door section and a lower door section vertically and oppositely movable on a pair of guides by a pair of flexible connectors.

One object of the invention is to provide a master operator for vertically sliding elevator doors by means of which one motor mounted on the car may be utilized to simultaneously open or close both the car door or gate and the hatchway door at the floor where the car is stopped.

Another object is to provide a master operator for vertically sliding elevator doors and car gates which may be easily and economically manufactured, installed, and maintained in operation.

Another object is to provide a master door operator in which a motor on the car may be used for opening a horizontally slideable door on a car and a vertically slideable door on the hatchway opening.

A further object is to provide an operator for vertically movable elevator doors and car gates in which the application of power to raise or lower the car gate may be applied in a horizontal direction to effect the raising or lowering of the hatchway door at which the car may be stopped.

A still further object is to provide a door operating system for elevator doors in which the operation of the vertically movable car gate may effect, by means of a horizontally traveling clutch, a corresponding movement of any vertical hatchway door at which the car may be stopped.

Other objects of the invention will be apparent from the following description, when taken in conjunction with the accompanying drawings, in which:

40 Figure 1 is a top plan view, partly in section, of an elevator door operator embodying my invention as installed at a landing at which a car is stopped;

Fig. 2 is a view in front elevation of the hatchway door and its operating mechanism, taken along the line II—II of Fig. 1;

Fig. 3 is a view in front elevation of part of the car gate operating mechanism, taken along the line III—III of Fig. 1;

50 Fig. 4 is a view in front elevation of the traveling clutch mounted on the car for operating the hatchway door, taken along the line IV—IV of Fig. 1.

Fig. 5 is a left-hand end view of the door operating mechanism illustrated in Fig. 1; and

Fig. 6 is a right-hand end view of the operator illustrated in Fig. 1.

Referring more particularly to the drawings, I have illustrated a portion of an elevator car C as disposed opposite a floor landing H represented by the hatchway walls 12 of an elevator hatchway having a plurality of floor landings.

The hatchway opening H is provided with a hatchway door 13 comprising an upper section 14 and a lower section 15 mounted upon a pair 16 of vertical guides 16 and 17 by means of a plurality of guide clips 18. The door is of the counterbalancing type in which the door sections move vertically and oppositely upon the guides when the door is being opened or closed. The means for connecting the door sections for the counterbalancing operation comprises a pair of flexible chain or cable connectors 20 and 21, the inner ends of which are fastened to a clevis 22 and a clevis 23 attached to clips 24 and 25 mounted on the lower outside edges of the upper door section 14. The center portion of the cable 20 passes over a first hatchway balancing sheave 26 to where its outer end is attached by means of a clevis 27 to the outer end of a bar 28 secured to the upper edge of the lower door section 15 by a plurality of bolts 29. The middle portion of the cable 21 passes outwardly over a second hatchway sheave 30 and over the central portion of a driving gear wheel 118 to a point where it is attached to a clevis 32 mounted on the right-hand end of the bar 28.

The sheave 26 is fixed on a shaft 34 rotatably mounted in the left end of a channel iron support 35 mounted on a pair of angle irons 36 and 36a secured to the hatchway door frame 37 in any suitable manner. Each rim of the sheave 30 is provided with gear teeth by means of which it may be driven and it is rotatably mounted on the end of a shaft 38 disposed in the right end 40 of the channel iron 35.

With this construction, it will be seen that the doors are suspended on the sheaves by the flexible connectors, which may be either cables or chains, and that the weight of the upper door section 45 tends to counterbalance the weight of the lower door section. Hence, by rotating the sheaves the connectors may be caused to move the door sections in opposite directions to either close or open the door.

Although I have illustrated only one hatchway door at one landing of an elevator, it is to be understood that similar doors and operating mechanisms may be installed at the other landings of the elevator.

The car is provided with a door or gate 39 comprising an upper section 40 and a lower section 41 (Figs. 1, 5 and 6) mounted on a pair of vertical guides 42 and 42a by means of a plurality of guide clips 43. The car door is of the counterbalanced type in which the door sections move vertically and oppositely upon the guides when the door is being opened or closed. The means for connecting the car door sections for their counterbalanced operation comprises a pair of flexible chains or cable connectors 44 and 45, the inner ends of which are fastened to clevises 46 and 47 attached to clips 48 and 49 mounted on the lower inside edges of the upper door section. The center portion of the cable 44 passes outwardly over a first car sheave 50 to where its outer end is attached by a clevis 51 to the outer end of a bar 52 (Figs. 5 and 6) secured to the upper edge of the lower section 41 of the car door or gate. The middle portion of the cable 45 passes outwardly over a second car sheave 54 to where its outer end is attached by a clevis 55 to the right-hand end of the bar 52.

By this construction, it will be seen that the sections of the car door are suspended on the sheaves by flexible connectors so that the weight of the upper section will counterbalance the weight of the lower section. Hence, by rotating the sheaves, the connectors or cables may be caused to move the car door sections in opposite directions to either open or close the door.

The means for rotating the car sheaves to open or close the car door comprises a motor 60 mounted on the top of the car. The shaft 61 of the motor is provided with a pinion 62 for driving a sprocket chain 63 which passes around a sprocket wheel 64 fixed on a shaft 65 also mounted on the top of the car by means of a pair of bearings 66. A pinion 67 smaller than the sprocket wheel 64 is fixed on the shaft 65 to drive a chain 68, the outer end of which passes around a sprocket wheel 69 fixed on a shaft 70, rotatably mounted in a pair of horizontal metal channel plates 71 and 72. The arrangement of these sprocket wheels, pinions and chains provides a speed reducing means which permits the use of a small high speed motor for opening and closing the doors. The channel plates are seated on a pair of angle irons 73 and 74 secured to the top of the car and extending out over the edge of the car in position to support the car door operating mechanism.

A gear wheel 76 is fixed on the shaft 70 in position to engage and drive an upper gear wheel 77 fixed to a shaft 78 rotatably mounted in the left end of the channel plate 71. A sprocket wheel 79 is fixed to the shaft 78 to be driven by the gear wheel 77. A sprocket chain 80 passes over the sprocket wheel 79 and thence over and around a sprocket wheel 81 fixed to a shaft 82 rotatably mounted in the right end of the channel irons 71 and 72. The sheave 50 is fixed on the shaft 70 and the sheave 54 is fixed on the shaft 82. Hence, when the motor 60 operates the chains 63 and 68 to rotate the sprocket wheel 69, that causes rotation of the shaft 70 and consequently the sheave 50. The rotation of the shaft 70 also rotates the gear wheel 76 which operates the gear wheel 77 and thereby rotates the sprocket wheel 79 to cause the chain 80 to drive the sprocket wheel 81 in an opposite direction, which rotates the shaft 82 thus rotating the sheave 54 in a direction opposite to that of the rotation of the sheave 50. The rotation of the sheaves in the 75 directions represented by the arrows 84 and 85

(Fig. 4) will cause the upper car door section 40 to be raised and the lower car door section 41 to be lowered, while rotation of the sheaves in the reverse direction will cause the upper car door section 40 to be lowered and the lower section 41 to be raised thereby closing the car door gate.

A clutch for causing the hatchway sheaves to operate the hatchway door in synchronism with the car door or gate is illustrated as comprising a driving block or carriage 90 mounted on the car and a drive block or carriage 91 mounted on the hatchway channel iron. The carriage 90 (Fig. 4) comprises a frame 93 supported upon a pair of wheels or rollers 94 which travel on a horizontal track rail 95 mounted in the lower part 15 of the channel iron 72. A grooved roller or wheel 96 is disposed in the upper part of the frame 93 to engage an upper guide rail 97, likewise mounted on the channel iron 72, for the purpose of guiding and maintaining the carriage 90 in an upright 20 position. A sprocket chain 98 is disposed around a sprocket wheel 99 and a sprocket idler wheel 100 with its ends secured to the ends of the frame 93. The sprocket wheel 99 is fixed on the shaft 70 and the idler wheel 100 is mounted rotatably 25 on channel plate 72. Hence, when these shafts are rotated by the motor 60 to open the car door, the sprocket wheels 99 and 100 are rotated in the direction of the arrows 84 and 85 to move the carriage 93 in a horizontal line to the right along 30 the track rail 95. An arm or vane 103 is mounted on the outer face of the driving carriage 90 for operating the driven carriage 91. The vane is disposed at right angles to the outer face of the carriage and extends a short distance above and below the carriage, so that it may operate the drive carriage even though the car may not be quite level with the floor landing. However, it will be obvious that if the car is more than half the 35 length of the vane away from the floor, the vane 40 will not open the hatch door, thus providing an additional safety factor.

The driven carriage 91 (Fig. 2) comprises a frame 105 supported on a pair of rollers 106 in position to ride on a horizontal rail 107 mounted 45 in the lower part of the channel iron 35. A grooved wheel or roller 107a is mounted in the upper part of the frame in position to engage a guide rail 108 mounted on the channel iron 35 for maintaining the carriage in a vertical position. The carriage 91 is provided with projecting arms 109, 110 which form a vertical slot 111 disposed to receive the vertical vane 103 on the carriage 90 when the car is opposite the hatchway door opening 11. The slot 111 is slightly wider 55 than the vane 103 so that the vane may move vertically through it without touching its walls when the car moves up and down the hatchway without stopping at the door-way 11. A sprocket chain 113 is disposed over a pair of sprockets 114 60 and 115 and around an idler sprocket 116 with its ends secured to the frame 105. The sprocket 116 is rotatably mounted on the channel iron 35 and its position may be adjusted to control the tension of the sprocket chain. The sprocket wheel 65 114 is fixed on the shaft 34 on which the hatchway sheave 26 is fixed, hence the sheave 26 will rotate with the sprocket wheel 114.

The sprocket wheel 115 is fixed on one end of a shaft 117 rotatably mounted in the channel iron 70 35. A gear wheel 118 is fixed on the other end of the shaft 117 to rotate with the sprocket wheel 115. The teeth of the gear wheel 118 are disposed to engage the cooperating gear teeth cut in the rims of the hatchway door sheave 30, so that ro- 75

tation of the gear wheel 115 will cause rotation of the sheave 30. The double gear wheel construction of the wheel 118 and the sheave 30 is utilized for the purpose of conserving space, it being easier to get a good driving connection between the thin gear wheels on both sides of the groove centers of the sheave 30 and the gear wheel 118 than it is to use a large gear on only one side of the sheave. In order to conserve further the size of the door operator, the shaft 117, the sprocket 115 and the gear wheel 118 are mounted somewhat below and to the right of the sheave 30, in which position the cable 21 runs over the sheave 30 and in around the inner face of the groove in the gear wheel 118.

A limit switch 120 for controlling the motor 60 at the ends of door travel is mounted upon the top of the car in position to be operated by a sprocket chain 121 disposed on a sprocket 122 mounted on the outer end of the shaft 82.

From the above description, it will be seen that, if the car stops opposite the hatchway floor and the motor 60 is energized, the shafts 70 and 82 will rotate, which, in turn, will rotate the sheaves 50 and 54 to open the car door sections 40 and 41. The rotation of the shafts 70 and 82 will also rotate the sprocket wheels 99 and 100 thus causing the chain 98 to move the carriage 90 in horizontal direction to the right. With the car at the floor, the vane 103 is in the slot 111. Consequently, the horizontal movement to the right of the vane causes it to impinge against the projecting arm 110 and move the carriage 91 to the right. This movement of the carriage 91 operates the driving chain 113 in the direction of the arrow 123 thereby rotating the sprocket wheels 115 and 114 in the direction of the arrows 124. This direction of rotation causes the shafts 34 and 117, on which these sprocket wheels are mounted, to rotate in the same direction, thus rotating the sheave 26 and the gear wheel 118 in the same direction. The rotation of the gear wheel 118 in the direction of the arrow 124 causes the sheave 30 to rotate in the direction of the arrow 125. Thus the rotation of the sheave 26 in the direction of the arrow 124 and the rotation of the sheave 30 in the direction of the arrow 125 causes the upper panel 14 of the hatchway door to rise and the lower panel 15 to drop to the level of the door sill, thus opening the hatchway door, at the same time that the rotation of the shafts 70 and 82 causes the sheaves 50 and 54 to raise the car door panel 40 and to lower the car door panel 41, thus opening the car door.

When it is desired to close the car door and the hatchway door, the motor 60 is reversed to rotate the car door sheaves 50 and 54 for the closing direction and at the same time move the carriage 90 from the right-hand side to the left-hand side of the door opening. This right to left movement of the carriage 90 causes the vane 103 to engage the projecting arm 109 on the driven carriage 91 and thereby move that carriage to the left, thus hauling the sprocket chain 113 around the sprocket wheels 114 and 115. This operation of the sprocket wheels 114 and 115 reverses the direction of operation of the sheaves 26 and 30, thus lowering the panel 14 and raising the panel 15 of the hatchway door and thereby closing the hatchway door simultaneously with the closure of the car door.

A hatchway door operating mechanism similar to the one illustrated and described may be installed at each door in an elevator shaft re-

presented by the walls 12 and the slot and vane construction on the driving carriage and the driven carriage will permit the car to run up and down the elevator shaft when the hatchway doors are closed without the vane engaging the driving arms.

A single panel door or gate may be substituted for the bi-parting car door shown in the drawings. Furthermore, the single panel may be made to operate in conjunction with the bi-parting hatch doors by introducing a 2:1 ratio between the car door sheaves and the driving sprockets.

Also, it will be obvious that a vertical door or gate on the car may be operated with a horizontally sliding hatch door by simply attaching the drive arms direct to the hatch door instead of mounting them on the driven carriage. Furthermore, a horizontally slideable door may be used on the car and vertically slideable door panels used for the hatch door.

By the foregoing description, it will be seen that I have provided an improved elevator door operator which requires only a single motor mounted on the car for opening a car gate and also the hatchway door at any floor at which the car stops. It will be obvious that this invention provides a simple structure by which a motive mechanism on the car may apply a horizontal drive to any vertically opening hatchway door opposite which the car may stop. It will also be obvious that the vertical driving vane on the car and the slot construction on the hatchway doors will permit the operating mechanism to be effective whenever the car stops at a floor even though it is not exactly level with the floor at which it stops. The system is particularly applicable for use in operating the car gates and hatchway doors of large freight elevators, but it may be used wherever vertically movable doors are desired.

Although I have illustrated and described only one specific embodiment of my invention, it is to be understood that changes therein and modifications thereof may be made without departing from the spirit and scope of the invention.

I claim as my invention:

1. In an elevator system having a car serving a hatchway landing, a vertically movable door at the hatchway landing, a vertically movable door on the car, a motive means mounted on the car, and means responsive to operation of the motive means on the car for vertically moving the car door and the hatchway door when the car is stopped at the hatchway door.

2. A door operating mechanism for a vertically slideable door on a car and a vertically slideable door on a hatchway served by the car, comprising a motor on the car, a driving block on the car, means responsive to operation of the motor for vertically moving the car door and for horizontally moving the driving block, a drive block mounted at the hatchway door in position to be engaged by the driving block and moved horizontally when the car stops at the floor and opens its door, and means responsive to the horizontal movement of the drive block for vertically moving the hatchway door.

3. In an elevator system, a car for serving a floor landing in a hatchway, a vertically slideable door at the floor landing, a vertically slideable door on the car, a driving block on the car, a plurality of flexible connectors and wheels connected to the car door and the driving block, a motor on the car for operating the connectors and wheels to move the car door in a vertical di-

rection and to move the driving block in a horizontal direction, a driven block associated with the hatchway door and disposed to be engaged and moved horizontally by the driving block when it is operated by the motor while the car is at the floor, and a plurality of wheels and flexible connectors connecting the driven block and the hatchway door to cause vertical movement of the hatchway door when the driven block is moved horizontally.

4. In an elevator system having a car operative in a hatchway, a door on the car having an upper section and a lower section vertically and oppositely movable on a pair of guides by a pair of flexible connectors disposed over a pair of car sheaves to close an opening in the car, a hatchway door having an upper section and a lower section vertically and oppositely movable on a pair of guides by a pair of flexible connectors disposed over a pair of hatchway sheaves to close an opening in the hatchway, a motor mounted on the car, means responsive to operation of the motor for rotating the car sheaves to operate the car door, a pair of car carriage driving wheels mounted on the car, means responsive to operation of the motor in operating the car door for operating the carriage wheels, a flexible driving member disposed around the car carriage driving wheels and operated thereby, a horizontal track mounted on the car, a car carriage disposed on the track between the car carriage wheels and attached to said flexible driving member whereby operation of the motor causes the carriage on the car to be moved in a horizontal direction, a horizontal track mounted at the hatchway door, a carriage mounted on said track, a pair of hatchway power wheels for rotating the sheaves to operate the hatchway door, a flexible driving member disposed around the hatchway power wheels and attached to the hatchway carriage to cause rotation of the hatchway door wheels when the hatchway carriage is moved along its track, and cooperating members on the hatchway carriage and the car carriage disposed to engage each other when the car is at the hatchway door and the motor is energized for causing the car carriage to move horizontally and thus move the hatchway car-

riage horizontally to effect operation of the hatchway door simultaneously with the car door.

5. In an elevator system having a car operated in a hatchway, a door on the car having an upper section and a lower section vertically and oppositely movable on a pair of guides, a frame on the car, a pair of rotatable shafts mounted on the frame, a motor for rotating the shafts, a pair of car sheaves mounted on the shafts, a pair of flexible connectors disposed over the car sheaves and connected to the car door sections for opening and closing the same when the motor is operated, a horizontal track on the car, a drive carriage disposed on the track, a pair of sprocket wheels mounted on the outer ends of the shafts, a flexible connector disposed around the sprocket wheels and connected to the drive carriage for moving it in a horizontal direction when the motor operates the car sheaves to open or close the car door, a hatchway door having an upper section and a lower section vertically and oppositely movable on a pair of guides attached to the hatchway, a track mounted at the hatchway door, a carriage mounted on the hatchway track, a pair of horizontal shafts mounted at the hatchway door, a pair of hatchway sheaves mounted on said hatchway shafts, a pair of flexible connectors disposed over said hatchway sheaves for raising or lowering the hatchway door sections, a hatchway sprocket wheel mounted on one of the shafts carrying one of the hatchway sheaves, a third shaft mounted at the hatchway door, gearing means mounted on said third shaft for engaging and operating the hatchway sheave on the other of said hatchway shafts, a hatchway sprocket wheel mounted on said third shaft, a flexible connector disposed over said hatchway sprocket wheels and connected to said driving carriage whereby operation of the driving carriage moves the hatchway door sections, and clutch means for connecting the drive carriage on the car with the driving carriage at the hatchway door when the car stops at the hatchway door to thereby cause operation of the hatchway door sections with operation of the car door sections.

ANDREW C. RADEEFF
